(57) **CLAIM**

The ornamental design for an exercise bike part, as shown and described.

DESCRIPTION

FIG. 1 is a front perspective view of an exercise bike part, showing my design.

FIG. 2 is a right and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is a reference view of the exercise bike part showing a status when the exercise bike part is assembled on an exercise bike.

The broken lines are for environmental structure, boundaries, or illustrative purposes only and form no part of the claimed designs to be patented.
